Application July 8, 1949, Serial No. 103,703

12 Claims. (Cl. 51—15)

1
This invention relates to the art of surface treating work pieces by the projection of abrasive particles at high velocity. This technique is known generally as grit blasting and is employed for the purpose of improving surface texture or quality, and particularly for the purpose of removing surface scale or adherent dirt or particles as in the treatment of rough sand castings and the like.

In conventional grit blasting methods, the abrasive particles, either sand, metal fragments or metal shot are propelled at high velocity upon the work surfaces by means of a blast of air, or by means of a so-called slinger which projects the particles through its own speed of rotation. The operation of grit blasting is a dusty one. Particles of the abrasive impacted on the surface of the work piece loosen dirt or scale either by attrition or by dislodgement and dust is liberated which pervades the atmosphere adjacent the work surface. The operation usually is conducted in the chamber of a grit blasting machine which is provided with a suitable exhaust system, but even so, the liberation of dust is a nuisance and, when the dust is of silicious nature, the operator is exposed to the dangers of contracting silicosis.

One of the principal objectives of this invention has been to provide grit blasting apparatus and improvements in the art of grit blasting by which dust formation is suppressed. More specifically, this invention contemplates a wet grit blast technique in which impaction and attrition of the abrasive particles upon the work occurs under wet conditions to such extent that any fine particles which normally would appear as airborne dust are dampened and thereby held against escape into the atmosphere.

Some grit blast machines have been built for the projection of a liquid slurry or suspension of abrasive upon work but in each instance of this sort, the abrasive particles are exceedingly fine, as for example, from 60 to 1200 mesh, the slurry being aspirated from a source of supply through an air blast nozzle. Such abrasive slurries are useful in the treatment of work surfaces to improve the surface texture or to remove light oxide films but the particles of such slurries are much too fine for use in the grit blasting of coarse castings or the like where removal of a substantial quantity of adherent sand or surface particles must be accomplished in a short period of time or where there is to be a material alteration of the work surface. The use of metallic grit of high specific gravity and large particle size in such

5 methods has been totally impossible; for example, grit particles or fragments up to $\frac{1}{8}$ inch in average diameter are much too heavy and dense, to be aspirated through a nozzle in an air blast or liquid stream and, of course, such particles cannot be pumped by ordinary methods.

10 This invention is predicated upon the concept and determination of establishing a dynamic suspension of grit blast particles of substantial size by forming a mixture of grit particles and liquid and advancing such a mixture at a low rate of velocity which is sufficiently high to keep the particles in a state of apparent suspension. Thus, the term, dynamic suspension, as used in this specification and throughout the claims is intended to designate a condition of distribution of grit particles in liquid which will be maintained while the liquid is in movement. Next, this stream moving at low velocity and keeping its particles in a state of suspension in so doing, is advanced to a projector which is effective for accelerating the velocity of the stream and the particles contained within it, up to the speed required for grit blasting. Otherwise expressed, 15 the invention in one respect is predicated upon the discovery that, while it is not possible to pump a liquid containing large particles of grit at grit blasting speed because of the attrition of the particles upon any conduit through which they must pass, still it is possible and practical to deliver a mixture of grit and water or liquid in an appropriate state of suspension of the particles up to the point of projection at a low velocity and then to impart additional energy to the particles which is requisite for them to accomplish the grit blasting function. This procedure eliminates the abrasion or wear which would otherwise be involved and enables all of the advantages and efficiency of a dry grit blast system to be obtained without the nuisance of dust. Furthermore, it is found that by conducting the blasting in the presence of liquid, a finer surface finish is produced.

20 25 30 35 40 45 50 To form the suspension, or more particularly, to advance a dynamic suspension of the particles or liquid, a pump somewhat akin to a centrifugal pump with provisions for introducing liquid and grit into it simultaneously has been found suitable. Such a pump, operated to advance the mixture at a low rate sufficient to dynamically suspend the particles, does not suffer excessive wear. From this point, the stream is advanced to a projector where the final high velocity is imparted to it. The projector either may be in the form of an air blast nozzle or in

the form of a slinger wheel and both embodiments by way of illustration are shown in the accompanying drawing. Following projection of the stream upon the work surfaces, which is conducted in a chamber on account of splashing, the grit and the dislodged dirt fall and the water drains to a sump. The grit, of course, falls almost immediately to the bottom while the water is allowed to accumulate in a layer above it. The layer of grit at the bottom constitutes a supply awaiting recycling to the low velocity pump. Meanwhile, however, it has been discovered that a substantial portion of the dirt dislodged from the work, in typical grit blasting operations, is sufficiently light in density as to form at least a temporary suspension in the water over the grit.

In common production operations, a system of the type just described would soon become overcharged with accumulated dirt since, in typical operations, the amount of dirt removed, for example as sand from a rough casting, is appreciable. However, an important feature of this invention is predicated on the concept of discharging a portion of the water accumulated over the grit into a settling or separatory apparatus where the suspended dirt is removed, as by common settling, from the water or liquid so as to leave the liquid in a relatively clean condition adapted to be recycled back to the machine. Thus, the clean suspension system and the dirt removal system may be in communication with one another through the chamber or the sump of the chamber in which blasting is conducted, with the dirt separation system functioning to condition the water for reuse. The advantage of this arrangement resides in the fact that the liquid portion of the treatment media is not subjected to dilution through constant additions of make-up liquid to it. Hence, the concentration of any added chemical such as a rust inhibitor or the like is not diluted.

In one embodiment, the invention incorporates a throwing wheel or slinger mounted on a resilient structure, which permits the wheel to rotate at blasting speed without transmitting vibrations to the apparatus. The grit particles are discharged by a nozzle into the interior of the wheel which has radial vanes, the grit particles being intercepted by the leading edges of the vanes which travel substantially at the same rate as the particles, whereby the grit particles are accelerated uniformly as they are propelled outwardly by the vanes toward the periphery of the wheel. The work pieces are conveyed upon a rotary table relative to the blasting wheel so that the pieces are treated by advancing them through the grit blast stream. In this instance, there is provided also a flushing station which projects jets of the settled or clarified liquid upon the work surface after treatment, to remove the foreign materials dislodged by the blast stream. The sump, which is disposed beneath the table, is arranged to contain a mass of grit particles and water, preferably containing a rust inhibiting solution, to protect the cleaned work surfaces. Grit particles and liquid thus fall by gravity from the work table to the sump for recirculation. In this form of apparatus, the work pieces are treated in batches for a time period as determined by the particular class of work, each piece of work being passed successively through the blast stream at a proper speed to obtain the desired result.

The apparatus is adapted for utilization in

well known commercial machines such as rotary tumbling mills, either the batch or continuous type, and also machines of the class incorporating a conveyor arranged to advance the work pieces through a treatment tunnel. As applied to rotary machines, one or more blasting wheels or other suitable projectors may be installed upon shafts extended into the tumbler so as to project grit streams upon the work pieces as they are agitated in the rotating tumbler or the wheel may be set to impel the grit into the open end of a tilted barrel. In conveyor type machines, one or more grit blasting wheels may be installed within the tunnel in positions to project the grit streams against opposite sides of the work pieces as they are advanced past the wheels by the conveyor. Also, work may be treated by placing it in fixed position in the blast stream for a timed, treatment period or by moving the projector relative to stationary work pieces.

From the foregoing disclosure of the principles involved, and from the detailed description taken in conjunction with the drawings, those skilled in the art will comprehend readily the various modifications of which the invention is capable.

In the drawings:

Figure 1 is a general front elevation of a grit blasting machine embodying the present improvements.

Figure 2 is a side elevation of the machine further illustrating the general arrangement of parts.

Figure 3 is a sectional view taken on line 3—3 of Figure 2, illustrating generally the internal structure of the machine.

Figure 4 is a horizontal sectional view taken on line 4—4 of Figure 3, illustrating the mounting arrangement for the grit blasting wheel with respect to the treatment chamber and the driving apparatus for the wheel.

Figure 5 is an enlarged fragmentary sectional view taken from Figure 3, detailing the relationship of the grit conveyor and the grit pump.

Figure 6 is a sectional view taken on line 6—6 of Figure 5, further detailing the construction of the grit pump.

Figure 7 is a fragmentary sectional view taken on line 7—7 of Figure 4, further detailing the yieldable mounting for the grit blasting wheel and its relationship with the work support table.

Figure 8 is an enlarged sectional view taken on line 8—8 of Figure 4, detailing the construction of the grit blasting wheel.

Figure 9 is a sectional view taken on line 9—9 of Figure 8, further illustrating the grit blasting wheel and the relationship of the grit supply nozzle with the wheel.

Figure 10 is an enlarged end view of a grit blasting wheel generally similar to that illustrated in Figure 8, the wheel being equipped with a modified form of a grit supply nozzle.

Figure 11 is a sectional view taken on line 11—11 of Figure 10, further illustrating the modified grit supply nozzle associated with the wheel.

Figure 12 is a view generally similar to Figure 7, with an air operated grit blasting nozzle substituted for the grit blasting wheel.

Figure 13 is an enlarged sectional view detailing the construction of the blast nozzle shown in Figure 12.

The apparatus disclosed in the drawings represents one organization by which the invention may be practiced and constitutes a treat-

ing machine having a rotary table arranged to convey work pieces successively through a grit blast stream and a rinsing station where the work pieces are flushed with a liquid solution, preferably water, containing a rust inhibitor. The grit and liquid are stored in a sump beneath the work table and in a settling tank respectively and recirculated continuously by a grit pump to the grit wheel and by a liquid pump to the spray pipe.

The grit particles preferably consist of metallic particles such as steel or metal shot, having a density substantially greater than water and greater than non-metallic grit. These particles settle quickly to the bottom of the sump to be conveyed mechanically to the grit pump, whereas the scale and dirt form a sludge of lesser density which remains in suspension at least temporarily in the water.

Since it is necessary to flush the work pieces with relatively clean water after grit blasting, the sludge is removed by drawing the liquid from the upper portion of the sump and passing it through a settling apparatus for removing the sludge before conducting the liquid to the spray pipe. Thus, one supply of liquid is drawn directly from the sump to provide a carrier for the grit particles, while another portion is drawn from the sump and clarified before being recirculated to the rinsing station.

Described with particular reference to Figure 3 of the drawings, the apparatus in general consists of a treatment chamber 15 having a rotary work support table 16, a grit blasting wheel 17 arranged to propel a blast stream of grit particles upon the work pieces carried by the table, and a spray pipe 18 arranged to flush the work pieces with jets of water or liquid solution after the grit blast treatment.

As above noted, the same solution preferably is used as a carrier for the grit particles and for the flushing treatment, there being provided a sump 19 in the base of the chamber for receiving the liquid and grit after passage over the work. The grit, which is considerably more dense than the liquid, settles almost immediately to the bottom of the sump after blasting to be recirculated to the blasting wheel. For this purpose there is provided a screw conveyor 20 in the sump bottom to feed the grit mechanically at a controlled rate to a grit pump 21 where it is mixed with liquor drawn from the sump and introduced into the pump, the liquid serving as a carrier so that the grit particles are conveyed with the liquid through a conduit to the blasting wheel.

The apparatus thus is provided with two separate circulatory systems, one system indicated generally at 22, being arranged to convey the mixture of grit and water from the pump to the blasting wheel and a second system, indicated at 23, arranged to draw off liquid from the upper portion of the hopper and to discharge the liquid into a settling apparatus for sludge removal, subsequently to be recirculated back to the spray pipe. The settling apparatus 24 is disclosed in the present instance as a pair of decanting tanks, although it is intended in connection with larger machines, to provide a sludge and sand removal apparatus having a mechanical conveyor passing through a settling tank for continuous operation.

In the present disclosure, the chamber 15 may be formed from sheet metal in the form of a square or rectangular housing having a pair

of converging side walls 25-25, forming the hopper or sump 19 which is generally V-shaped as viewed in Figure 2. The side walls form a conveyor trough 26 in which is rotatably mounted the conveyor screw 20, arranged to feed the grit particles to the grit pump 21 located at one end of the trough.

As viewed in Figure 3, the conveyor trough and screw are inclined downwardly toward the grit pump to facilitate movement of the grit particles. As shown, there is provided a well 28 rising from the grit pump and open to the sump to maintain a liquid level common to that in the sump to permit the grit to be fed directly by the conveyor into the grit pump. In operation a liquid passes with the grit into the pump, and an additional supply of liquid is drawn from the upper level of the sump and discharged into the bottom of the pump to prevent any accumulation of grit in the pump bottom.

At the front of the housing, there is provided a door 30 for loading and unloading the work table and for general utility in operating and servicing the machine (Figures 1, 2 and 4). The door is supported at its upper end by a pair of inclined lugs 31-31 welded or otherwise secured to the chamber adjacent the door opening (not shown). The door includes a pair of studs 32-32 secured upon its upper edge and projecting outwardly from opposite sides and resting upon the lugs. The lower edge of the door is confined by a vertical flange 33 secured to the housing beneath the door opening and spaced from the housing so as to slidably confine the edge of the door between the flange and housing. In closed position, the lower edge of the door is held against the housing by the flange 33 and the upper edge by the inclined lugs 31. The door includes a handle 35 by which it may be lifted out of engagement with the lugs and flange and either removed entirely or swung to an open position for access into the chamber. Along the opposite sides of the door opening, there is mounted a pair of brackets 36-36 angularly related to the housing and designed to maintain the door in an inclined position in front of the door opening with the lower edge of the door resting against the housing. During operation of the machine, the door is kept closed to prevent grit particles from being discharged from the machine, although for observation purposes, the machine may be operated with the door partially open, as above noted.

As shown, the machine is supported by vertical legs 37 formed preferably from angle irons, the upper ends of the legs being welded or otherwise secured to the chamber as at 38. The lower ends of the legs are connected to a framework 39 which braces the legs and provides a support for the driving mechanism of the grit conveyor as hereinafter disclosed.

Grit conveying apparatus

As illustrated in Figure 3, the sump 19 provides a common reservoir for a supply of grit particles indicated at 40 and the liquid, preferably consisting of water, indicated at 41, including a rust inhibitor compound. In operation, a continuous supply of grit is advanced by the conveyor to the grit pump 21 and, at the same time, a supply of liquid is drawn from the sump by conduit 42 and introduced into the bottom of the pump casing at the center thereof (Figure 2). The grit particles are fed into the center of the pump impeller

from above by the conveyor, as illustrated in Figure 5. By operation of the impeller, the grit particles are intermingled with the liquid and discharged into the flexible conduit 43 which leads to the grit blasting wheel or slinger 18. The mixture is conducted through the conduit at a velocity sufficient to maintain the particles in dynamic suspension, but insufficient to perform the blasting operation or to cause substantial wear upon the pump or conduit. The upper end of the conduit 43 passes through the housing and is connected to the blasting wheel nozzle in the manner shown in Figure 4 or alternately, to the air blast nozzle as shown in Figures 12 and 13.

Described in detail, the grit conveyor constitutes a spiral vane or screw which includes a shaft 44 having its opposite ends journaled in bearings 45 and 46. The shaft extends through the upper bearing 45 and includes a sprocket 47 for driving the screw. Since bearing 45 is below the liquid level in the sump, it is provided with a packing gland to prevent leakage of liquid. The packing gland and bearing is a commercial product and, for this reason, is not disclosed in detail. The lower bearing 46 is mounted upon the top of the pump casing within the well 28, submerged in the liquid. Both bearings are provided with suitable seals to protect the bearing surfaces against the entry of grit particles and sand.

The driving apparatus for the conveyor screw preferably is a commercial variable speed unit mounted upon a base plate 48 supported by the legs 31 and framework 39 beneath the sump (Figures 1, 2 and 3). The unit, in general, consists of a motor 50 having a variable diameter V-belt pulley 51 of conventional construction. The motor pulley 51 is connected by a V-belt 52 to a V-belt pulley 53 mounted on the shaft of a speed reducer unit 54. On the opposite end of the speed reducer, there is provided a sprocket 55 which is connected to the conveyor sprocket 47 by a chain 56. Conveyor speed is regulated by shifting the motor relative to the speed reducer unit. For this purpose, the motor is mounted upon an adjustable base 57 having a hand wheel 58 arranged to shift the motor relative to the speed reducer and thus to change the effective diameter of the motor pulley. By virtue of the variable speed unit, the rate of grit feed to the blast wheel may be regulated according to the particular requirements of the operation.

The lower or discharge end of the conveyor screw feeds the grit in the presence of the liquid maintained above the pump, directly into the grit pump through an opening 59 formed by a collar 60 mounted in the top wall of the pump casing (Figures 5 and 6). Since the conveyor screw is provided with a single spiral vane 61, it will be evident that the discharge of grit will be intermittent, that is to say, there will be a concentrated discharge each time the trailing end of the vane makes one revolution through the lower zone of the conveyor trough. In order to provide a continuous discharge, a device is provided which regulates the flow of grit particles by restricting the passage of material from the conveyor to the grit pump.

This device consists of a collar 62 welded or otherwise secured in the end wall 63 of the hopper and provided with a stationary control disk 64 secured within the collar and operating in conjunction with a disk 65 secured to and rotatable with the screw shaft 44. As shown in Figures 3 and 5, the rotary disk 65 includes blades 66 which are pitched in the same direction as the screw vane 61

61 while the blades 67 of the stationary disk are pitched in the opposite direction. The rotary blades 66 preferably have a collective pitch equal to one turn of the screw vane and the stationary blades have an equal pitch in the opposite direction. It is found that this arrangement effectively regulates the discharge of grit without building up back pressure against the conveyor screw.

Grit pump

The grit pump consists of a circular casing 68 having a rotor or impeller generally indicated at 69, enclosed within the casing by end plate assemblies 70 and 71 (Figures 5 and 6). The casing 68 includes upper and lower circumferential flanges 72-72. The end plate assemblies are secured by means of bolts 73 passing through matching apertures located at spaced intervals around the circumference of the pump. The inner ends of the bolts are provided with nuts and washers 74 and 75. Each of the end plate assemblies 70 and 71 consist of a pair of metal plates 76-76 having a sheet 77 of rubber, synthetic rubber or the like interposed in compression between the plates.

The impeller consists of a pair of disks 78-78 spaced apart from one another and having a series of spiral vanes 79 interposed between the spaced plates and secured by welding. Above and below the respective plates, there is provided secondary sets of spiral vanes 80 and 81 which supplement the pumping action of the vanes 79. It will be noted that the collar 60 extends through a central opening formed in the top disk 78 of the impeller so that the material discharged from the conveyor passes through the collar directly into the pumping zone between the impeller disks for actuation by the inner or leading edges 82 of the vanes 79. As shown in Figure 6, the inner edges of vanes 79 and 80 terminate at the outside diameter of collar 60 while the inner ends 83 of the secondary vanes 81 extend inwardly to the hub 84 which is welded as at 85 to the lower impeller disk.

Liquid is introduced through the bottom of the pump through a pipe 86 connected to the flexible tube or hose 42, the opposite end of which communicates with the hopper at a point above the level of the grit mass but below the liquid level. The liquid flows into the pump casing and is impelled radially by operation of the lower vanes 81 to prevent accumulation of grit particles at the bottom of the pump. The mixture of grit and liquid introduced through the opening 59 also flows radially from between the impeller disks so that the grit particles are picked up by the moving stream of solution at the bottom of the casing and intermingled with it for discharge into the pump outlet 87. Outlet 87 constitutes a section of pipe generally tangent to the pump impeller, the pipe being welded to an opening formed in casing 68. The casing includes a partition 88 at one side of the opening to complete the passageway from the pump casing to the outlet. The mixture of grit and liquid is conducted by the flexible conduit 43 from the outlet 87 upwardly to the grit blasting wheel as hereinbefore disclosed. Pipe 86 preferably includes a fitting 89 including a valve 90 for draining the liquid from the sump.

The previously noted pump well 28 is in the form of a cylindrical shell formed of sheet metal and having its vertical edges 91 secured by welding to the end wall of the hopper. This struc-

ture provides a mounting for the pump, the upper plate 76 of the pump being secured to the lower edge of the shell by welding as at 92 (Figure 5).

The pump is driven by means of a vertical shaft 93 journalled in bearings 94-94 secured to the end wall of the chamber and driven by a motor 95 mounted near the top of the chamber (Figures 1, 2 and 3). Upon the upper end of the shaft 93 there is provided a V-belt pulley 96 connected by belts 97 to a V-belt pulley 98 mounted on the motor shaft. The lower end of the pump drive shaft passes downwardly through the well 28 and has its lower end keyed to the hub 84 of the pump impeller.

The grit impeller is detachably secured to the shaft 93 by a screw 99 passing through a segment 100 which is welded as at 101 to the inside diameter of the hub 84 (Figures 5 and 6). The segment fits into a notch 102 cut into the end of the shaft so as to key with the segment and provide a driving connection between the hub and shaft. The segment is formed most conveniently by cutting it from the end of the shaft so as to form the notch 102 in the shaft corresponding in shape to the segment. The segment then is welded into the hub as shown and is drilled to provide a hole for the screw 99, which is threaded into the shaft, preferably with the parts in assembly.

Grit blasting wheel

The mixture of liquid and grit from the grit pump is conducted by the tube 43 to discharge the mixture into the grit blasting wheel 103 as shown in Figures 7 and 9. This wheel slings the grit by centrifugal force upon the work pieces supported beneath the wheel upon the rotary table 16, the blast stream being fan-shaped so as to cover substantially one-half the diameter of the table in the manner indicated in broken lines in Figure 7. In order to discharge the particles at sufficient velocity for the blasting operation, a high peripheral wheel speed is necessary. In a given size wheel, this velocity is obtained by driving the wheel at a speed of approximately 4,000 R. P. M. Since the grit velocity is determined by the peripheral speed of the wheel, it will be apparent that a smaller diameter of wheel necessarily is driven at a greater speed than a larger one. The speed also is determined by the grit size and the class of work being cleaned.

By reason of velocity, there is a pronounced tendency for the wheel to set up vibrations which ordinarily are transmitted to the entire machine, causing noisy operation and undue wear on the wheel bearings. This condition is substantially eliminated by resiliently mounting the wheel and nozzle assembly with respect to the chamber. For this purpose, there is provided a spring mounted frame 104 disposed in a horizontal plane above the work table, the frame providing a bearing for supporting the wheel and also a mount for the grit nozzle 105, the nozzle being mounted in fixed relationship and in axial alignment with the wheel center. By this arrangement, the wheel floats relative to the blasting chamber so that upon reaching a settling speed, it is free to rotate about a center which may be slightly eccentric to its true center. The arrangement eliminates the necessity of accurately balancing the wheel. Since the discharge nozzle is fixed upon the same frame 104, vibration of the wheel does

not alter the relationship between the nozzle and wheel.

The frame 104 is made up preferably of angle iron sections 106 suitably joined together to provide a rigid structure. The nozzle 105 is mounted by means of a pillow block 107 bolted as at 108 to the frame, the nozzle being adjustably secured with respect to the pillow block by means of a set screw 109 passing through block 107. The discharge end of the nozzle is curved as at 110 approximately at right angles to the body of the nozzle. By this arrangement, the grit is projected directly into the inner or leading edges of the vanes of the grit blasting wheel and as hereinafter disclosed, the angle of discharge from the wheel can be regulated by rotary adjustment of the nozzle.

As shown in Figure 9, the grit blasting wheel consists of a pair of rotor disks 111 and 112 spaced from each other and provided with a series of spiral vanes 113 joined to the disks preferably by welding. Disk 111 includes a hub 114 by means of which the wheel assembly is mounted upon the end of a drive shaft 115. The wheel is detachably secured by means of the screw 116 passing through a segment 117 and screw-threaded into the end of the shaft, the segment fitting into a notch 118 to key the wheel to the shaft. This arrangement is similar to that disclosed in connection with the grit pump and the circular segment, in this case also, may be formed by cutting it from the end of the shaft in the manner previously noted. Shaft 115 is journalled in a bearing 119 secured by screws 120 to the frame structure on the side opposite to the nozzle. The shaft extends through the end wall of the chamber and is journalled in a bearing 121 secured to the wall. Bearings 119 and 121 preferably are ball bearings of commercial design, the bearing 121 being of the type which permits angular shaft motion, whereby the wheel assembly is free to vibrate without injury to the bearing. The respective bearings are protected by stuffing boxes or slinger rings 122-122, one being secured to the inner surface of the chamber wall, the other being mounted upon a rail 123 spanning the frame 104. The stuffing boxes may be of any design suitable to prevent the entry of grit particles into the bearings.

The frame 104 is yieldably mounted by the spring units 124 connected to the respective corners of the frame, the opposite ends of the spring units being anchored upon angle irons 125 and 126 located on opposite sides of the frame. The inner mounting angle iron 125 is mounted within the chamber with its ends secured preferably by welding to the walls of the chamber. The other angle iron 126 is secured upon the outside surface of the chamber wall, also by welding. Each tension unit constitutes a link 127 having one end pivotally connected to the corner of the frame by a screw 128 and having its opposite end connected to a plunger 129 by a pivot pin 130. A spring 131 is disposed under compression upon the plunger, one end of the spring being seated against a rubber grommet 132 seated against the vertical web 133 of the angle iron 125. The opposite end of the spring rests against a washer 134 engaged by a nut 135 screwed upon the end of plunger 129. By means of these nuts the tension of the respective units is adjusted and equalized with respect to one another to align the wheel assembly properly with respect to the bearing 121. By exerting tension in opposite directions, the frame is maintained in

11

tension in a level plane and by virtue of the springs and pivotal action of the links 127, the wheel assembly is free to vibrate in vertical and horizontal planes and thereby prevent the transmission of vibration and noise to the machine and to permit the wheel to find its natural center of rotation.

As shown in Figures 3, 4 and 7, there is provided a semi-circular shroud or grit shield 136 extending over the upper circumference of the blasting wheel. The lower ends of the shroud include a pair of angular extensions or feet 137, formed by bending the ends outwardly. The feet are secured by means of bolts 138 passing through the angle irons 104. The purpose of the shield is to prevent stray grit particles from being projected against the top and side walls of the chamber; also to prevent the particles from being projected towards the door opening with possible injury to the operator should the door be left open.

The vanes 13 of the grit blasting wheel are spirally arranged between the disks 111 and 112, the edges of the vanes being secured to the respective disks by welding. As above disclosed, disk 111 is secured to the drive shaft 115 and provides a mounting plate for the wheel while disk 112 includes an opening 140 for entry of the discharge nozzle 105. As shown in Figure 7, the leading edges 141 of vanes 113 are disposed closely adjacent the opening 140 in a position to intercept the stream of grit and liquid discharged from the nozzle 105.

The initial discharge velocity of the stream is substantially the same as the velocity of the leading vane edges 141 so as to reduce the impact of the particles against the leading edges and thus prevent excessive vane wear. By virtue of the configuration of the vanes, the grit particles are accelerated at a fairly uniform rate as the particles slide from the leading edges toward the trailing edges at the circumference of the wheel by centrifugal action. By regulating the angle of the discharge nozzle 105, the discharge path of the blast stream can be regulated with respect to the work table so as to cause the particles to strike the proper portion of the table. As indicated in Figure 7, in broken lines, the path of the particles generally is fan shaped and tangent to the wheel. The angle of the stream is determined by the velocity of the wheel in conjunction with the angle of the discharge nozzle. The driven speed of the wheel necessarily is regulated by the size of the grit particles and the class of work being blasted. In setting up the machine, it is necessary to adjust the angle of the nozzle according to these factors in order to achieve maximum efficiency.

The wheel is driven by any acceptable means, for example by a motor indicated at 142 (Figures 1 and 2). The wheel is connected to the motor by a pulley 143 keyed upon the outer end of shaft 115 and driven by a V-belt 144 passing over a pulley 145 mounted on the shaft of the motor. The rate of grit feed to the blasting wheel, as previously noted, is controlled by adjustment of the variable speed unit so that operating characteristics can be governed accurately.

Work support table

During the grit blasting operation, the work table 16, which is circular, is rotated by a friction pulley 146, engaged against the circumference of the table by a lever 147 which is pivotally

12

mounted as at 148 between a pair of angle irons 150-150 mounted within the chamber (Figures 3 and 4). The lever urges the pulley toward the table under the influence of a spring 151 having one end hooked upon the outer end of the lever as at 152 and having its opposite end anchored upon the chamber wall as at 153. The lever 147 is U-shaped as viewed in Figure 3, having limbs 154-154 with the pulley disposed between the limbs and driven by a shaft 155. The pulley is keyed to the shaft and the shaft journaled in the limbs 154-154.

Shaft 155 rises vertically to a speed reducing unit 156 mounted on the top of the chamber. In order to permit angular movements of the pulley 146, a universal joint 157 is interposed in the shaft. The speed reducer 156 is driven from the grit pump shaft 93 by means of a V-belt 158 passing over pulley 96 of the pump shaft and extending to a standard type of variable speed idler pulley 159, adjustably mounted upon the top of the chamber to regulate the speed of the table. The speed reducer 156 is driven by a second V-belt 160 passing over the variable idler pulley 159 and pulley 161 of the speed reducer. The table thus is rotated by the same motor 95 which drives the grit pump.

The table is rotatably mounted by a shaft 162 journaled in a pair of spaced bearings 163-163. Bearings 163 are mounted upon a frame 164 constituting spaced angle irons 165-165 secured within and extending crosswise of the chamber. A strap 166 extending crosswise between the angle irons supports the upper bearing and the lower bearing is supported by a hanger structure 167 extending downwardly from the angle irons.

In operation, the grit particles and liquid impinge upon the work pieces, then drop to the hopper for recirculation. For this purpose, the table includes suitable apertures (not shown) and there is provided also beneath the table a screen 168 spaced above the hopper to prevent castings, which may be dislodged from the table, from dropping into the hopper. The screen is of a mesh which is sufficiently coarse to permit the grit particles to pass without interference.

A slightly modified grit nozzle arrangement is illustrated in Figures 10 and 11. As shown, the nozzle 170 is located generally at a tangent with respect to the direction of wheel rotation as viewed endwise (Figure 10). In order to introduce the discharge end of the tube into the blasting wheel, the nozzle is extended angularly into the opening 140 of disk 112 instead of being in axial alignment with shaft 115 as illustrated in Figure 11.

The discharge end 171 of the nozzle in this instance is formed by cutting the end of the nozzle at an angle which is related chordwise to the radius described by the leading edges of the vanes (Figure 10). One advantage of this arrangement is that the grit particles travel more nearly in a straight line through the nozzle to the leading edges of the vanes as distinguished from the change in direction caused by the curved nozzle 105. The stream is intercepted by the leading edges of the vanes and is accelerated uniformly by reason of the increasing peripheral speed as the grit particles advance toward the trailing edges of the vanes.

The nozzle 170 is adjustable with respect to the axis of the blasting wheel in the manner previously disclosed, by the pillow block 107, and set screw 109. In order to sustain the nozzle body at an angle and at the same time to permit

the nozzle to be adjusted radially, the nozzle is supported by an arm 172 welded or otherwise secured to a shaft 173, passing through the bearing block 107 in place of the nozzle 105. By rotating the shaft, which is on the same axis as shaft 115 of the wheel, the discharge end 171 swings in an arc concentric with the radius described by the leading edges of the vanes to control the discharge angle of the grit blast stream.

Liquid spray system

In operating the apparatus, the work pieces are treated for a predetermined time period according to the class of work, type of material and other determining factors. Each treatment is a continuous one, the work pieces passing through the blast stream for treatment after which the pieces sequentially pass beneath a spray pipe for exposure to jets of liquid to remove the sand, sludge and other materials dislodged by the grit treatment. The spray treatment also removes from the work pieces any particles of grit which may adhere. The liquid then drains to the sump for recirculation. As previously noted, the liquid contains a rust inhibitor of a type conventionally used in cleaning metal parts.

Described in detail, the spray pipe indicated at 174 in Figures 3 and 4 extends radially across the table at the forward section of the chamber and is provided with a series of apertures to project the liquid in jets upon the pieces carried by the table. The liquid is supplied to the spray pipe by the recirculating system 23 previously noted. The liquid flows from the sump by gravity through the pipe 175 opening into the chamber near the liquid level in the sump. The liquid in the sump is substantially free of grit particles but contains sand, scale and sludge which has been dislodged from the castings. Since the flushing is performed most efficiently with a clear solution, the liquid drawn off from the sump passes through the separator for removal of the solids before recirculation. The separator disclosed is in the form of decanting tanks 176 and 177 although it is contemplated in connection with larger equipment to provide a mechanical separator, as previously noted. The tank 176 is provided with an overflow passageway 178 so that the liquid flowing from the sump is maintained in the first tank for preliminary settling period before passing through the overflow 178 to tank 177. The liquid is drawn from tank 177 by a pump 179 mounted upon the wall of the chamber and driven by a V-belt 180 passing over a pulley 181 mounted upon the grit pump shaft. Pump 179 is a commercial product and therefore is not disclosed in detail. The liquid is drawn from the tank by the tube 182 and is conducted from the pump to the spray pipe by a tube 183 passing through the housing 124 with its end connected to the spray pipe.

Air blast nozzle

In place of the grit blasting wheel, the grit may be blasted by air pressure, utilizing a nozzle by which high velocity air jets are introduced into the stream of liquid and grit discharged by the grit pump. As shown in Figure 12, the nozzle occupies approximately the same position as the blasting wheel and is connected to the flexible tube 43, leading from the grit pump. The blast nozzle constitutes generally a transition chamber 184, a blast nozzle 185 and an air chamber 186 surrounding the blast nozzle at a point intermediate of its length to apply secondary air jets to the stream passing through the nozzle to raise 75

the velocity of the stream to its final blasting force.

Described in detail, the chamber 184 includes a plate 187 secured by screws 188 upon the flat side of the chamber, there being provided an opening 189 in the wall to permit entry of an air jet tube 190 which extends angularly into the chamber. To the outside of plate 187, there is secured an air intake nozzle 191 to which is connected a supply tube 192 which conducts compressed air from a supply unit (not shown). The air blast passes through tube 190 which includes at its lower end a jet 193, directed toward the intake end of nozzle 185. The stream of grit flows around the tube 190 in passing through chamber 184 and its velocity is increased by the introduction of air through the jet as the stream passes into the restricted opening formed by collar 194 which forms the discharge end of the chamber. The nozzle 185 is connected to the collar 194 by a coupling 195 screwthreaded upon the collar 194.

The nozzle 185 is oval as viewed in cross section and is flared downwardly to provide a diverging passageway so as to form a fan-shaped blast stream. In passing through the nozzle, the stream is further accelerated by the air chamber 186 which constitutes a housing preferably welded upon the outside of the nozzle to form an air manifold 196. The air is introduced into the manifold by a nipple 197 which is connected to a second compressed air supply line 198. Air passes at high velocity into the moving stream by means of a series of jet apertures 199 drilled at an angle through the wall of the nozzle so as to direct the air jets into the stream at an angle to the direction of discharge. This arrangement provides substantially the same velocity and volumetric discharge of grit as provided by the grit blasting wheel.

The nozzle is mounted above the work table by means of a vertical shaft 200 having its lower end clamped in a socket 201 welded to one side of the transition chamber (Figure 12). The shaft is clamped in the socket by means of a set screw 202 threaded through the socket. Shaft 200 passes through the top wall of the treatment chamber and through a collar 203 welded to the underside of the wall. A set screw 204 is threaded into the collar to engage and lock the shaft and nozzle assembly in adjusted position with respect to the work table.

Having described my invention, I claim:

1. A method of grit blasting which comprises mechanically feeding grit particles to a pump at a controlled rate and therein forming a dynamic suspension of grit particles in liquid, moving the mixture of the grit particles and liquid at a low rate of velocity, and then imparting energy to the moving stream sufficient in amount to cause projection of the dynamic suspension at a high rate of velocity which is sufficient to perform a grit blasting function.

2. The method of grit blasting with grit particles which are incapable of suspension in liquid in the absence of movement which comprises mechanically feeding grit particles and concurrently advancing liquid to a low velocity centrifugal pump, and thereby forming a dynamic suspension of the grit particles in the liquid in the form of a stream moving at low velocity, advancing the low velocity stream to a projector and therein accelerating the rate of movement of the stream to a high velocity effective for grit blasting, then collecting and recycling the components of the mixture to the pump.

3. An apparatus for wet blasting work pieces

with grit particles which are incapable of suspension in liquid in the absence of movement comprising; a chamber, a grit projector in the chamber adapted to propel a stream of grit and liquid against the work pieces at blasting velocity, the chamber being adapted to receive the grit particles and liquid discharged by the projector, conveyor means in the chamber adapted to feed grit particles from the chamber, at a controlled rate and a pump adapted to receive said grit particles and liquid from the chamber and to propel the mixture to the projector at a velocity sufficient to maintain the grit particles in dynamic suspension in the liquid but insufficient to perform the blasting operation.

4. An apparatus for wet blasting work pieces with grit particles which are incapable of suspension in liquid in the absence of movement comprising; a chamber, a grit projector in the chamber adapted to propel a stream of grit and liquid against the work pieces at blasting velocity, the chamber being adapted to receive the grit particles and liquid discharged by the projector, conveyor means in the chamber adapted to feed grit particles from the chamber at a controlled rate, a separatory apparatus communicating with the chamber and arranged concurrently to separate suspended particles of dirt from the liquid, and a pump adapted to receive said grit particles and liquid from the chamber and to propel the mixture to the projector at a velocity sufficient to maintain the grit particles in dynamic suspension in the liquid but insufficient to perform the blasting operation.

5. An apparatus for wet grit blasting work pieces comprising; a chamber, work supporting means within said chamber, a grit projector adapted to propel a stream of grit and carrier liquid at blasting velocity upon the work pieces, a hopper in said chamber adapted to receive the grit particles and liquid discharged by the projector, conveyor means in said hopper adapted to feed a supply of grit particles from said hopper at a controlled rate, and a pump adapted to receive said grit particles and to mix the particles with carrier liquid drawn from the hopper and to propel the mixture to said grit projector at sufficient velocity to maintain the grit particles in dynamic suspension in the carrier liquid.

6. A wet grit blasting apparatus for the surface treatment of work pieces comprising; a chamber adapted to contain a supply of grit particles and liquid, a grit pump mounted adjacent the chamber, a screw conveyor mounted within the chamber and communicating with the grit pump, a device associated with the screw conveyor arranged to feed the grit particles at a constant rate into the grit pump, means connected to the chamber above the level of grit particles and adapted to supply liquid from the chamber to the grit pump, a grit projector mounted within the chamber, and means connected to said pump to convey the liquid and grit to the projector at a velocity sufficient to maintain the particles in dynamic suspension in the liquid, the projector being arranged to accelerate the grit particles to a blasting velocity for impingement upon the work surfaces.

7. An apparatus for wet blasting work pieces with grit particles which are incapable of suspension in liquid in the absence of movement comprising; a reservoir adapted to contain a supply of grit particles and carrier liquid, a grit pump associated with the reservoir and adapted to intermingle the grit particles and liquid and

to discharge the mixture at sufficient velocity to maintain the grit particles in dynamic suspension, a grit projector for accelerating the mixture to blasting velocity, a conduit connecting the grit pump to the said grit projector for advancing the grit particles and liquid to the projector, means for advancing work pieces relative to the projector for impingement of the blast stream upon the work pieces, spray means adapted to project flushing liquid upon the work pieces, a pump for supplying liquid to the said spray means, said pump being connected to the reservoir above the level of the grit particles to conduct the carrier liquid from the reservoir for discharge to the said spray means.

8. An apparatus for wet blasting work pieces with grit particles which are incapable of suspension in liquid in the absence of movement comprising; a reservoir adapted to contain a supply of grit particles and carrier liquid, a grit pump associated with the reservoir and adapted to intermingle the grit particles and liquid and to discharge the mixture at sufficient velocity to maintain the grit particles in dynamic suspension, a grit projector for accelerating the mixture to blasting velocity, a conduit connecting the grit pump to the said grit projector, means for advancing work pieces relative to the grit projector for impingement of the blast stream upon the work pieces, spray means adapted to project flushing liquid upon the work pieces after passage through the grit blast stream, a pump for supplying liquid to the said spray means, said pump being connected to the reservoir above the level of the grit particles to conduct the carrier liquid from the reservoir for discharge to the said spray means, and an apparatus for removing from the carrier liquid the foreign particles dislodged by the blast stream prior to the passage of the liquid to the spray means to provide a clear liquid for cleaning the work pieces.

9. A wet grit blasting apparatus comprising; a hopper adapted to contain a mass of grit particles and carrier liquid, a grit pump mounted adjacent the hopper and in communication therewith, a conveyor screw mounted within the lower portion of the hopper and extending to the grit pump, the hopper having a grit discharge passageway communicating with the pump for passage of the grit particles advanced by the conveyor screw, a rotary control disk having blades mounted upon the conveyor screw for rotation therewith, the disk being disposed within the discharge passageway, a stationary control disk secured within the said passageway adjacent the rotary control disk, said disks being adapted to control the passage of grit particles through the passageway to the grit pump, means for supplying carrier liquid to the pump, and a projector connected to the pump adapted to accelerate the grit particles to blasting velocity.

10. A wet grit blasting apparatus comprising; a chamber, a hopper in the lower portion of the chamber adapted to contain a mass of grit particles and carrier liquid, a grit projector adapted to propel a stream of grit and carrier liquid at blasting velocity, a grit pump mounted externally of the hopper, a conveyor screw rotatably mounted within the lower portion of the hopper, the hopper having a passageway communicating with the grit pump, said conveyor screw being extended through said passageway whereby the grit particles are fed by the screw conveyor to the grit pump in the presence of the carrier liquid, means for withdrawing carrier liquid from

the hopper above the grit particles therein and conducting the same to the grit pump, and conduit means extending from the grit pump to the grit projector, the grit pump being adapted to mix the grit particles and carrier liquid and to propel the mixture to the grit projector at sufficient velocity to maintain the grit particles in dynamic suspension in the carrier liquid.

11. A wet grit blasting apparatus comprising; a chamber, a hopper in the chamber adapted to contain a mass of grit particles and carrier liquid, a grit projector adapted to propel a stream of grit and carrier liquid at blasting velocity, a grit pump mounted externally of the hopper, a conveyor screw mounted within the lower portion of the hopper, the hopper having a passageway communicating with the grit pump, said conveyor screw being extended through said passageway whereby the grit particles are fed by the screw conveyor to the pump in the presence of the carrier liquid, a compartment externally of the hopper and extending upwardly from the pump, the compartment being adapted to maintain a carrier liquid level above the pump externally of the hopper at the level of the carrier liquid in the hopper, means for withdrawing carrier liquid from the hopper above the grit particles therein and conducting the same to the grit pump, and conduit means extending from the grit pump to the grit projector, the grit pump being adapted to mix the grit particles and carrier liquid and to propel the mixture to the grit projector at sufficient velocity to maintain the grit particles in dynamic suspension in the carrier liquid.

12. A wet grit blasting apparatus comprising; a chamber, a hopper in the chamber adapted to contain a mass of grit particles and carrier liquid, a grit projector adapted to propel a stream of grit particles and carrier liquid at blasting velocity, a grit pump casing mounted externally of the hopper, the grit pump casing having a top including an opening to receive grit particles, an impeller within said casing, a conveyor screw mounted

within the lower portion of the hopper, the hopper having a passageway and said conveyor screw being extended through said passageway whereby the grit particles are fed by the screw conveyor to the opening in the top of the grit pump casing in the presence of the carrier liquid, a compartment externally of the hopper extending upwardly from the top of the pump casing and adapted to maintain the carrier liquid above the pump casing at the level of the carrier liquid in the hopper, a drive shaft connected to the pump impeller and extending upwardly through said compartment, conduit means extending from the hopper to the bottom of the grit pump casing adapted to conduct carrier liquid from the hopper to the grit pump casing, and conduit means extending from the grit pump casing to the grit projector, the grit pump impeller being adapted to mix the grit particles and carrier liquid and to propel the mixture to the grit projector at sufficient velocity to maintain the grit particles in dynamic suspension in the carrier liquid.
